UNITED STATES PATENT OFFICE

HARRY ALPHONSE WIDMER, OF LONDON, ENGLAND, ASSIGNOR TO TUCK-TITE LOCK AND
FASTENER COMPANY LIMITED, OF LONDON, ENGLAND, A COMPANY OF GREAT
BRITAIN

FASTENING

Application filed May 24, 1930, Serial No. 455,268, and in Great Britain March 26, 1930.

The present invention relates to improvements in stud and spring socket fastenings and is applicable for use on handbags and other articles or containers in which such 5 fastenings are necessary or desirable.

Briefly stated the present invention comprises a fastening of this character with a double action adapted to be first unlocked and then disconnected by continuous pressure on the stud. The stud comprises an element, a sleeve and a spring working in a cylinder.

According to the invention the stud and an inner-unlocking sleeve are mounted on a 15 spring and the combined member is adapted to be pressed back against the influence of said spring through an opening in the socket to release the stud from the socket grip.

Our invention is shown by way of example in the accompanying drawing, in 20 which—

Figure 1 shows a sectional view of the stud and spring socket fastening in the fastened 25 position.

Figure 2 shows a plan view of the stud. Figure 3 shows a section on the line III—III of Figure 2.

Figure 4 shows a sectional side view on the line IV—IV of Figure 3.

Figure 5 shows a plan view of the spring 30 socket fastening with the cover removed to show the working parts.

Figure 6 shows a section on the line VI—VI of Figure 5.

Figure 7 shows a sectional view, with the 35 spring omitted, of the parts in the first intermediate position of release, and

Figure 8 shows a sectional view of the 40 parts shown in Figure 7 in the second intermediate position of release.

In the drawing 1 indicates the stud and 45 2 the spring socket shown more particularly in Figures 5 and 6. As shown in Figure 1 these members are mounted on the parts to be engaged of the container or bag to be fastened. In a leather bag, for instance, the stud is mounted on the body portion 3 while the spring socket or fastening is mounted on the flap portion 4, the body and the grip 50 may be secured to the fastening device by

clamping as indicated in Fig. 1, the clamp portion being secured by rivets shown in Fig. 6 of the drawing.

The element 1 of said stud is preferably 55 spherical shaped as shown and is developed into a neck of cylindrical form at the lower end which telescopes into the cylinder mounting 5, and is slidably supported thereby by the projecting lugs 7 on opposite sides, 60 which engage and slide in the slots 18 in the cylinder 5. The element 1 is hollow and forms a sliding support for the sleeve 12 which is provided at its upper end with a rounded, or domed head. This sleeve projects through the element as indicated in 65 Fig. 4. The integral construction of the stud requires that the sliding motion of the sleeve 12 be limited relative to the element 1, as for instance between the upper position indicated in Fig. 3 and the lower position indicated in Fig. 8. In order to limit the outward sliding movement of the sleeve 12 with respect to the element 1, the ends of the spring 6 are suitably secured to cylinder 5 and sleeve 12 respectively. The coil 70 spring 6 engages the bottom. The spring grip fastening is conveniently in the form of two engaging members 8 with cut out portions 9 therein adapted to engage around the neck of the element 1 and to enter the slots 13 therein when in the fastened position shown in Figure 1. These members 8 slide in the frame 11 and are under the influence of their bow springs 10 and consequently are held up against the neck of the element in engagement in the said slots 13 when the parts are in the fastened position.

As shown more particularly in Figures 1, 7 and 8, the end 14 of the domed sleeve 12 is turned inwards and the engaging edges 90 15 of the gripping members 8 are chamfered in order that the members 8 may be easily pushed apart by the sleeve 12 when the latter is pressed into the element 1.

In order to fasten the flap 4 to the body 95 of the container or bag the spring socket mounted on the flap is pressed over the stud, thus opening apart the locking members 8 as the stud head passes through the opening 9. The engaging edges 100 15 of the

members 8 grip the neck of the element and enter the slots 13 therein as shown in Figure 1 and thus positively fasten the flap to the body of the bag. When it is desired to release the fastening the domed end of the sleeve 12 is pressed and the sleeve pushed down into the element against the influence of the spring 6 thus pushing the members 8 apart as shown in Figure 7 and allowing the element 1 to be pushed through the grip fastening, into the cylinder 5 thus easily and instantaneously releasing the flap from the body of the bag or the like.

What I claim is:—

- 15 1. A spring socket fastener comprising a spring grip mounted on the closing member of the article to be fastened and a stud comprising a cylinder with an element sliding in said cylinder mounted on the body of the article to be fastened and provided with a neck adapted to be positively engaged by said spring grip, a spring, and a sleeve in said element adapted to move the members of said grip outwardly to release said stud by pressure on said sleeve, said spring engaging the bottom of cylinder and the top of said sleeve.
- 20 2. A spring socket fastener comprising a grip mounted on the closing member of the article to be fastened, spring controlled engaging members mounted in said grip and a stud comprising a cylinder with an element sliding in said cylinder mounted on the article to be fastened, said element having recesses in its neck adapted to be positively engaged by the spring controlled members of the grip, a spring, and a sleeve sliding in said element adapted to move the members of said grip outwards to release said stud by pressure on said sleeve, said spring abutting on said cylinder and on said sleeve.
- 25 3. A spring socket fastener comprising a spring grip mounted on the closing member of the article to be fastened, a stud comprising a cylinder with an element therein mounted on the article to be fastened, said element provided with a neck adapted to be positively engaged by said spring grip, a spring and an unlocking member slidably mounted in the head of said element adapted to be pressed down to unlock the spring grip from the neck of the element by moving the members of said grip outwardly before said stud is pushed through the grip, said spring abutting on said cylinder and on said unlocking member.
- 30 4. A spring socket fastener comprising a spring grip mounted on the closing member of the article to be fastened, a stud comprising a cylinder mounted on the body of the article to be fastened, an element slidably mounted in said cylinder with a neck adapted to be positively engaged by said spring grip, a spring and means embodied in and movable relative to said element for releas-

ing said stud by pressure on said means, said spring abutting on said cylinder and on said means.

5. A spring socket fastener comprising a spring grip mounted on the closing member of the article to be fastened, a stud comprising a cylinder mounted on the body of the article to be fastened, an element slidably mounted in said cylinder with a neck adapted to be positively engaged by said spring grip, a spring, means embodied in said stud for unlocking said grip by pressure thereon and opposite lugs on the inner end of said element adapted to engage in corresponding vertical guiding slots in the wall of said cylinder said spring abutting on said cylinder and on said means.

6. A spring socket fastener comprising a grip mounted on the closing member of the article to be fastened, spring controlled engaging members mounted in said grip, a stud comprising a cylinder mounted on the body of the article to be fastened, an element having a neck slidably mounted in said cylinder with recesses in its neck adapted to be positively engaged by the spring controlled members of the grip, a spring and means embodied in and movable relative to said element for disengaging said grip from said neck by pressure on said means said spring abutting on said cylinder and on said means.

7. A spring socket fastener comprising a spring grip secured to one of the members to be fastened, a stud secured to the other member to be fastened, said stud comprising a cylinder, an element, a sleeve and a spring mounted in said cylinder, said element being slidable in said cylinder and being engaged by said grip in the normal position, said sleeve being movable from its normal position relative to said element to disengage said grip from the stud and said spring abutting on said cylinder and on said sleeve to maintain said element in the normal position.

8. A spring socket fastener comprising a spring grip having a pair of spaced members secured to one of the members to be fastened, a stud secured to the other member to be fastened, said stud comprising a cylinder, an element, a sleeve and a spring mounted in said cylinder, said element being arranged to pass between said spaced members on said spring grip, being slidable in said cylinder and being engaged by said grip in the normal position, said sleeve being movable relative to said element to disengage said grip from the stud and said spring maintaining said element away from the releasing position.

9. A spring socket fastener comprising a spring grip mounted on the closing member of the article to be fastened, a stud comprising a cylinder with a closed inner end

mounted on the body of the article to be fastened, an element slidably mounted in said cylinder with recesses in its neck adapted to be positively engaged by said spring 5 grip, an unlocking member slidably mounted in the head of said element, and a spring arranged in said cylinder between its closed inner end and the unlocking member and adapted to be compressed in said cylinder 10 when said unlocking member is pressed down to unlock the spring grip from the neck of said element before the stud is pushed through said grip.

10. A spring socket fastener comprising 15 a spring grip mounted in the closing member of the article to be fastened, a stud comprising a cylinder with a closed inner end mounted on the body of the article to be fastened, an element slidably mounted in 20 said cylinder with recesses in its neck adapted to be positively engaged by said spring grip, a domed sleeve forming an unlocking member slidably mounted in the head of said element and a spring arranged in said 25 cylinder between its closed inner end and the domed sleeve adapted to be compressed in said cylinder when the domed sleeve is pressed down to unlock the spring grip from the neck of said element before the stud is 30 pushed through said grip.

11. A spring socket fastener comprising a grip mounted on the closing member of the article to be fastened, spring controlled 35 engaging members mounted in said grip, a stud comprising a cylinder with a closed inner end mounted on the body of the article to be fastened, an element slidably mounted in said cylinder with recesses in its neck adapted to be positively engaged by the 40 engaging members of said grip, a domed sleeve forming an unlocking member slidably mounted in the head of said element, and a spring arranged in said cylinder between its closed inner end and the domed sleeve in 45 said element adapted to be compressed in said cylinder when the domed sleeve is pressed down to unlock said engaging grip members from the neck of the element before the stud is pushed through said grip.

50. 12. A spring socket fastener comprising a grip mounted on the closing member of the article to be fastened, a pair of opposite sliding engaging members with adjacent cut out 55 portions mounted in said grip, bow springs behind said engaging members adapted to press them towards each other, a stud comprising a cylinder with a closed inner end mounted on the body of the article to be fastened, an element slidably mounted in said cylinder with recesses in its neck adapted to be positively engaged by the 60 engaging members of said grip, a domed sleeve forming an unlocking member slidably mounted in the head of said element, and a spring arranged 65 in said cylinder between its closed inner end

and the domed sleeve in said element adapted to be compressed in said cylinder when the domed sleeve is pressed down to unlock said engaging grip members from the neck of the element before the stud is pushed 70 through said grip.

13. A spring socket fastener comprising a grip mounted on the closing member of the article to be fastened, a pair of opposite sliding engaging members with adjacent chamfered cut out portions mounted in said grip, bow springs behind said engaging members adapted to press them towards each other, a stud comprising a cylinder with a closed inner end mounted on the body of the article to be fastened, an element slidably mounted in said cylinder with recesses in its neck adapted to be positively engaged by the engaging members of said grip, a domed sleeve forming an unlocking member 80 slidably mounted in the head of said element and having an inwardly turned open inner end adapted to engage the chamfered cut out portions of said engaging members and a spring arranged in said cylinder between its closed inner end and the domed sleeve in said element adapted to be compressed in said cylinder when the domed sleeve is pressed down to unlock said engaging 85 grip members from the neck of the element before the stud is pushed through said grip.

14. A spring socket fastener comprising a grip mounted on the closing member of the article to be fastened, a pair of opposite sliding engaging members with adjacent chamfered cut out portions mounted in said grip, bow springs behind said engaging members adapted to press them towards each other, a stud comprising a cylinder with a closed inner end mounted on the body of the article to be fastened, an element slidably mounted in said cylinder with recesses in its neck adapted to be positively engaged by the engaging members of said grip, a domed sleeve forming an unlocking member slidably mounted in the head of said element and having an inwardly turned open inner end adapted to engage the chamfered cut out 90 portions of said engaging members, a spring arranged in said cylinder between its closed inner end and the domed sleeve in said element adapted to be compressed in said cylinder when the domed sleeve is pressed down to unlock said engaging grip members from the neck of the element before the stud is pushed through said grip.

15. In testimony whereof I have signed my name to this specification.

HARRY ALPHONSE WIDMER.
